CLAIM

The ornamental design for a camping lantern, as shown and described.

DESCRIPTION

FIG. 1 is a front elevation view of a camping lantern showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top left perspective view thereof; and,

FIG. 8 is a bottom left perspective view thereof.

The broken lines in the figures are for the purposes of illustrating portions of the camping lantern, which form no part of the claimed design.

1 Claim, 8 Drawing Sheets
